Fig. 1 is a perspective view of the right side of a self-propelled swather, showing the platform assembly raised, embodying my new design.

Fig. 2 is a perspective view of the front thereof showing the platform assembly raised.

Fig. 3 is a perspective view of the left side thereof showing the platform assembly lowered; and

Fig. 4 is a perspective view of the rear of said self-propelled swather showing the platform assembly lowered.

The dominant features of the design reside in the portions shown in solid lines.

I claim:

The ornamental design for a self-propelled swather, as shown and described.
